UNITED STATES PATENT OFFICE.

E. F. FRENCH, OF NEW YORK, N. Y.

IMPROVED COVERS FOR SEWING-MACHINES.

Specification forming part of Letters Patent No. 98,485, dated January 4, 1870.

To all whom it may concern:

Be it known that I, E. F. FRENCH, of the city, county, and State of New York, have invented a new and useful Improvement in Covers for Sewing-Machines; and I do hereby declare that the following is a full, clear, and exact description of the same, reference being had to the accompanying drawings, making a part of this specification.

The nature of my invention consists in constructing covers for sewing-machines in such a manner that they will not warp or spring, and still be equally as strong and durable as those now ordinarily manufactured, have a neater or more ornamental appearance, and admit of being made equally as cheap.

Hitherto the covers for sewing-machines have been constructed in simple box-form—four sides, of equal thickness, secured at the angles or corners by dovetails, miter-joints, or other connections. These covers, in consequence of being thus constructed, frequently warp or spring, and, even when made of well-seasoned wood, are often returned to the manufacturer to be repaired, and sometimes require to be replaced by new ones.

By my improvement I not only avoid this difficulty, but also obtain the advantage of having a cover which will admit of being taken apart and packed within a very limited space, so as to economize in transportation, and also admit of being put together with the greatest facility at any time when required.

To effect this I make my cover in the usual form, rectangular, as that probably would be the most desirable shape. The cover is constructed of a frame, in which panels, which compose the sides of the cover, are inserted, the panels, of course, being made out of much thinner stuff than the frame, and all so arranged that the several parts which comprise the cover may be taken apart and put together again with the greatest facility, the panels being fitted loosely in grooves in the inner edges or surfaces of the parts composing the frame, so that said panels may shrink without the liability of splitting, and swell, without straining the frame or forcing the cover out of proper shape.

In the accompanying sheet of drawings, Figure 1 is a side view of my invention; Fig. 2, a transverse vertical section of the same, taken

in the line *x x*, Fig. 1; Fig. 3, an inverted plan of the same, partly in section.

Similar letters of reference indicate corresponding parts in the several figures.

To enable those skilled in the art to fully understand and construct my invention, I will proceed to describe it.

The frame of the cover is composed of uprights or stiles *a*, of any suitable wood, connected by horizontal rails or cross-pieces *b*. These stiles and cross-pieces are properly framed together by tongue and groove, or other suitable joints, as shown in Fig. 3, at *c*. The frame has a panel, *d*, fitted within it at each side, the panels being of much less thickness than the stuff of which the parts composing the frame is made. (See Fig. 2.) These panels are fitted in grooves *e*, made in the inner edges of the uprights or stiles and the cross-rails of the frame, as shown in Figs. 2 and 3.

In practice I design to have these parts so made that they may be fitted together and taken apart without any trouble or difficulty whatever. By this means I can, in shipping the covers in quantities, have the parts of each cover disconnected, so that a large number of covers may be packed within a small compass or space, and when they have arrived at their destination, or at any time after when desired, be put together and made ready for use.

In putting the several parts of a cover permanently together, the stiles and cross-pieces of the frame may be glued at their joints, but the panels *d* are not glued in the grooves in the stiles and rails, and the panels, therefore, are allowed to shrink, if they shrink at all, without being liable to check, crack, or split.

The top *e* of the cover may be constructed similarly to its sides, and fitted to the top rails by dowel-pins *f*, or other suitable means. (See Fig. 2.)

By this mode of construction I obtain a sewing-machine cover which is free from the principal objections attending those as ordinarily made, checking by shrinkage being avoided, the covers admitting of being readily put together and taken apart, to economize in transportation, and having a far neater appearance than those as now made.

I am aware that sewing-machine covers have been made with moldings tacked, glued, or otherwise secured to their exterior, so as to imi-

tate paneling or a panel-make. This, however, although giving to a cover the same appearance as one constructed according to my invention, has none of the essential advantages of the latter, as the difficulty attending shrinkage is not avoided, no economy effected as regards the amount of timber or stuff used in the manufacture.

I would remark that the uprights or stiles may be composed each of one or more longitudinal pieces, connected together by glue or otherwise. The drawings, however, represent them as being formed each out of one piece, and this I prefer.

Having thus described my invention, what

I claim as new, and desire to secure by Letters Patent, is—

The herein-described cover for sewing-machines, the same consisting of stiles *b b*, solid corners *a a*, the top frame *e*, and the side and top panels *d*, set loosely in grooves, as and for the purpose set forth, when the parts are constructed, arranged, and combined as specified, so that the cover can be taken apart for transportation, as described.

E. F. FRENCH.
